UNITED STATES PATENT OFFICE.

HUGH LOGIE ALLAN, OF AYR, SCOTLAND.

OIL-REFINING APPARATUS.

1,390,742.

Specification of Letters Patent. Patented Sept. 13, 1921.

Application filed April 18, 1916. Serial No. 92,026.

To all whom it may concern:

Be it known that I, HUGH LOGIE ALLAN, a subject of the King of the United Kingdom of Great Britain and Ireland, and resident of 46 Park Circus, Ayr, Scotland, have invented certain new and useful Improvements in Oil-Refining Apparatus, of which the following is a specification.

The invention relates to the fractional distillation and dephlegmation of petroleum or other hydrocarbons or mixture of liquids of different boiling points including shale and coal distillates hereafter described as substances.

15 The invention relates particularly to the operations referred to namely the continuous fractionation and continuous dephlegmation of substances as hereinbefore described.

Existing plants of this general type merely fractionate, the present invention refractonates and dephlegmates; further existing apparatus called dephlegmators are designed so that portions of the substance vaporized are continually and recurringly condensed and 25 returned to the original substance and the original substance by this method gradually becomes a concentrate of fractions with higher boiling points than those which are desired in the distillate, or distillates.

30 The continual return of condensed lighter fractions to the said concentrated substance makes this method of separation of the various fractions desired laborious as regards time, limits the capacity of the plant, is expensive in fuel and is less efficient in every way than the present invention.

The present invention provides improved means of progressively separating the various fractions of different boiling points and 40 density in the substances quoted in a cheaper and more efficient manner than heretofore known.

No part or portion of the substance (substances) evaporated returns to the vessel or 45 still from which it is originally evaporated but goes progressively forward through as many units proposed by the present invention as may be necessary to obtain the quality of product desired.

50 A very large portion of the substance evaporated goes forward as stated and is not condensed until it reaches the unit or units where it is ultimately desired and hence has not been subjected to the frequent and ex-

pensive condensations and reevaporations 55 of the older or existing methods.

The present invention utilizes the latent heat of the fractions condensed in each unit to assist the forward movement of lighter fractions and very little additional heat is 60 required to maintain the reevaporation necessary in each unit.

Reference is made to the accompanying drawing which shows by way of example a single unit of an apparatus, capable of carrying out the functions herein set forth.

Figure 1 is an elevation of the apparatus—partly in section.

Fig. 2 is an elevation looking at right angles to Fig. 1.

70 1 is a cast iron or steel vessel of suitable dimensions or form which acts as container and concentrator of condensed fractions; 2, 3 are metal tubes of convenient dimension and shape or design which condense the 75 vapors passing through them either by the medium of the surrounding atmosphere or if desired by means of water supplied through distributors 4, and caught in catchment tray 5, metal anti-splash cone 6 being 80 provided.

7, 8 are metallic headers or boxes connecting the pipes 2, 3 from unit to unit or apparatus to apparatus.

The vessel 1 is fitted with a closed coil 85 9 which either by steam, hot oil or other heating medium provides the additional heat required to reevaporate such fractions as may not be desired in a particular unit.

10 is an open steam pipe through which 90 steam can be admitted to the apparatus to further concentrate the contents or fraction condensed in the vessel 1, 11 is a gage glass, 12 an exit pipe fitted to run off to suitable receiver, condensed fractions when desired. 95

The gases or vapors, from any form of still distilling substances as mentioned, enter the apparatus through header or connecting box 7, pass via tube 2 into 1 and thence through tube 3 and header or connecting box 8 to the 100 next unit or ultimately, to a water condenser.

The whole apparatus is inclosed in suitable building to protect from extreme weather variations.

Claim.

An oil refining apparatus, comprising in combination a plurality of vaporizing units, uptake pipes extending from said units,

downcomer pipes opening into said units and connections for connecting the uptake pipes of one unit to the downtake pipes of the adjacent unit, means for heating said 5 units, and means for cooling said downcomer pipes, which comprises cooling liquid distributors surrounding the upper ends of said

pipes, an anti-splash device disposed at the end of said pipes, and a collecting tray for collecting the cooling liquid.

HUGH LOGIE ALLAN.
